CROCHET NEEDLE

Frederick Franz, West Haven, Conn., assignor to
 C. J. Bates & Son, Chester, Conn., a partnership

Application August 15, 1944, Serial No. 549,527

4 Claims. (Cl. 66—118)

1

The present invention relates to improvements in crochet needles, and one of the main objects of the present invention is to provide a crochet needle which will be convenient and reliable in use.

Another object of the present invention is to provide a superior crochet needle which, when of a given size, will produce substantially identical results from user to user despite wide variations in the respective techniques of the users.

A further object of the present invention is to provide a simple, reliable and effective crochet needle which will facilitate the operation of the pulling-through of one loop of a strand through another loop thereof.

Still another object of the present invention is to provide a superior crochet needle which will permit the pulling of one loop of a strand through another loop thereof without unduly distending or stretching the last-mentioned loop.

A still further object of the present invention is to provide a superior crochet needle which will produce uniform results in the crocheted material.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of one form of crochet needle embodying the present invention;

Fig. 2 is a broken face view of the upper-portion of the crochet needle;

Fig. 3 is a view of the upper-portion of the crochet needle looking in the direction of the arrow 3 of Fig. 1;

Fig. 4 is a broken view of the upper-portion of the crochet needle looking in the direction of the arrow 4 of Fig. 1;

Fig. 5 is a broken transverse sectional view taken on the line 5—5 of Fig. 1;

Fig. 6 is a transverse sectional view taken on the line 6—6 of Fig. 2;

Fig. 7 is a top or plan view of the crochet needle and showing a strand wrapped therearound preparatory to drawing one looped-portion thereof through another looped-portion thereof;

Fig. 8 is a broken view in side elevation of the showing of Fig. 7;

Fig. 9 is a top or plan view similar to Fig. 2

but showing the step of drawing one looped-portion of the strand through another looped-portion thereof; and

Fig. 10 is a broken view in side elevation of the showing of Fig. 9.

The crochet needle illustrated in the accompanying drawings for purposes of making clear one form of the present invention, may be made of any suitable material such as metal, wood, bone, synthetic resins, etc., and includes a rod-like body 10 having a conoidally-shaped outer end and provided with an obliquely-disposed head 11. Below its head 11, the body 10 is formed with an inclined strand-accommodating groove 12 which is of substantially-U-shaped longitudinal form, as well as of substantially-U-shaped form in cross section, as is especially well shown respectively in Figs. 5 and 4.

The strand-accommodating groove 12 above referred to extends longitudinally in a direction which is oblique with respect to the longitudinal axis of the body 10 and has its upper wall provided by the under face of the head 11, which latter has a central nose- or hook-portion 13.

With the formation of the strand-accommodating groove 12 results in the production of what may be aptly termed "a neck-portion" 14 which integrally connects the main portion of the body 10 with the head 11.

The U-shaped longitudinal form of the strand-accommodating groove 12 comprises a curved connecting-reach at the front of the neck-portion 14 and two complementary side-reaches respectively extending on opposite sides of the said neck-portion. Both of the said side-reaches, as well as the connecting-reach, have corresponding U-shaped cross-sectional form and are overhung by the under face of the head 11. Furthermore, it will be noted that both of the said side-reaches, as well as the connecting-reach, are bisected by a common plane (such as the plane along the line 5—5 of Fig. 1) which is oblique with respect to the longitudinal axis of the needle.

The portion of the body 10 lying immediately below the central part of the hook-portion 13 is sloped to produce a throat-portion 15 which is preferably slightly convex in cross section, as is especially well shown in Fig. 6, and affords a strand, such as 16, ready access to the groove 12.

In Figs. 7 to 10 inclusive the crochet needle above described, is shown in conjunction with the strand 16 of textile material which, in the instance shown, is exaggerated in diameter for purposes of clarity, as is also the depth of the

strand-accommodating groove 12 for the same purposes.

In Figs. 7 and 8 the strand 16 has a portion 17 (an incipient loop) which is shown as extending across the throat-portion 15, beneath the hook-portion 13 and in a portion of the strand-accommodating groove 12. The part of the strand 16 below the portion 17 just referred to, extends around the body 10 in the form of a loop 18 in a manner common in crocheting practice, as one phase of the crocheting operation.

By drawing downwardly upon the body 10 whilst holding the loop-portion 18 from also descending, the portion 17 and the loop 18 of the strand 16 will be brought into the relative positions in which they are indicated in Figs. 9 and 10. In the figures just referred to it will be noted that the portion 17 of the strand 16 has enveloped the neck-portion 14 by its entry into the oblique strand-accommodating groove 12, and has thereby had its outer boundary brought within the boundaries defined by the diameter of the body 10 throughout substantially the entire length of the said portion 17. The continued downward movement of the crochet needle with respect to the loop 18, will draw the now-looped portion 17 through the said loop 18 without requiring appreciable stretching or distention of the latter.

Thus, the substantially complete accommodation of one looped-portion of a strand within the strand-accommodating groove 12 or its equivalent, facilitates the drawing of such a looped-portion through another looped-portion of the strand. In this manner, the operation just referred to is so simplified as to enable a user to produce uniform results without undue effort and with great rapidity.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A crochet needle having a body provided at one end with an obliquely-disposed head connected to the body proper by a relatively-slender neck, the needle being formed inwardly of the said head with a strand-accommodating groove of substantially-U-shaped longitudinal form and extending longitudinally in a direction oblique with respect to the longitudinal axis of the body, the longitudinal U-shaped form of the said strand-accommodating groove comprising a curved connecting-reach at the central throat-portion of the said neck and two side-reaches on the respective opposite sides of the said neck, each of the said reaches also being of substantially-U-shaped form in cross section with the inner wall of each of said reaches having a cross-sectional form substantially corresponding to the cross-sectional form of the inner wall of the others of said reaches and being bisected by a common plane which is oblique with respect to the longitudinal axis of the needle; the under face of the said obliquely-disposed head overhanging all three of the said reaches of the strand-accommodating groove and providing the upper wall thereof.

2. A crochet needle having a body provided at one end with an obliquely-disposed head con-

nected to the body proper by a relatively-slender neck, the needle being formed inwardly of the said head with a strand-accommodating groove of substantially-U-shaped longitudinal form and extending longitudinally in a direction oblique with respect to the longitudinal axis of the body, the longitudinal U-shaped form of the said strand-accommodating groove comprising a curved connecting-reach at the central throat-portion of the said neck and two side-reaches on the respective opposite sides of the said neck, each of the said reaches also being of substantially-U-shaped form in cross section with the inner wall of each of said reaches having a cross-sectional form substantially corresponding to the cross-sectional form of the inner wall of the others of said reaches and being bisected by a common plane which is oblique with respect to the longitudinal axis of the needle; the longitudinal form of the inner surface of the connecting-reach of the said strand-accommodating groove being substantially semicircular; the under face of the said obliquely-disposed head overhanging all three of the said reaches of the strand-accommodating groove and providing the upper wall thereof.

3. A crochet needle including a substantially-cylindrical body having a conoidal end formed with an obliquely-disposed head connected to the cylindrical body proper by a relatively-slender neck, the needle being formed inwardly of the said head with a strand-accommodating groove of substantially-U-shaped longitudinal form and extending in a direction oblique with respect to the longitudinal axis of the cylindrical body, the longitudinal U-shaped form of the said strand-accommodating groove including a curved connecting-reach located at the central throat-portion of the said neck and inclined upwardly from a point substantially at the junction of the body proper and its said conoidal end, the said strand-accommodating groove also including two side-reaches located on the respective opposite sides of the said neck, each of the three said reaches being also of substantially-U-shaped form in cross section with the inner wall of each of said reaches having a cross-sectional form substantially corresponding to the cross-sectional form of the inner wall of the others of said reaches and being bisected by a common plane which is oblique with respect to the longitudinal axis of the needle; the under face of the said obliquely-disposed head overhanging all three of the said reaches of the strand-accommodating groove and providing the upper wall thereof.

4. A crochet needle including a substantially-cylindrical body having a conoidal end formed with an obliquely-disposed head connected to the cylindrical body proper by a relatively-slender neck, the needle being formed inwardly of the said head with a strand-accommodating groove of substantially-U-shaped longitudinal form and extending in a direction oblique with respect to the longitudinal axis of the cylindrical body, the longitudinal U-shaped form of the said strand-accommodating groove including a curved connecting-reach located at the central throat-portion of the said neck and inclined upwardly from a point substantially at the junction of the body proper and its said conoidal end, the said strand-accommodating groove also including two side-reaches located on the respective opposite sides of the said neck, each of the three said reaches being also of substantially-U-shaped form in cross section with the inner wall of each of said reaches

having a cross-sectional form substantially corresponding to the cross-sectional form of the inner wall of the others of said reaches and being bisected by a common plane which is oblique with respect to the longitudinal axis of the needle; the longitudinal form of the inner surface of the connecting-reach of the said strand-accommo-

5 dating groove being substantially semicircular; the under face of the said obliquely-disposed head overhanging all three of the said reaches of the strand-accommodating groove and providing the upper wall thereof.

FREDERICK FRANZ.
